William E. Schmidt
BY
Frank H. Fowler
ATTORNEY

UNITED STATES PATENT OFFICE.

WILLIAM E. SCHMIDT, OF SEATTLE, WASHINGTON.

EYE-SHIELD.

1,217,838.

Specification of Letters Patent.

Patented Feb. 27, 1917.

Application filed October 18, 1915. Serial No. 56,846.

To all whom it may concern:

Be it known that I, WILLIAM E. SCHMIDT, a citizen of the United States, and a resident of Seattle, in the county of King and State of Washington, have invented certain new and useful Improvements in Eye-Shields, of which the following is a full, true, and exact specification.

My invention relates to improvements in eye shields and has for its principal object to provide a cheap, simple and novel device for protecting the eyes and face from flying pieces of metal, emery and the like from lathes, grinding wheels and the like. A further object is to provide a device of this character which will be removably attachable to a tool post of a lathe or the like and to provide means for adjusting the position of the shield, which is transparent. Other objects will appear as my invention is more fully explained in the following specification, illustrated in the accompanying drawings and pointed out in the appended claims.

In the drawings, Figure 1 is a front elevation of my device. Fig. 2 is a side elevation of same. Fig. 3 is a front elevation of a modified form of my device with parts of the shield broken away. Fig. 4 is a side elevation of Fig. 3.

Referring more particularly to the drawings, numeral 1 indicates a forked clamp having a clamping screw 2. A channeled shield support 3 is secured to the top of clamp 1. A transparent shield 4 is supported by shield support 3. The shield 4 is preferably of glass but may be of any transparent material. The shield is held in the support by screws 5 or may be cemented in place. Referring to Figs. 3 and 4, the forked clamp consists of a head 6 with spring fork members 7, one secured to either side of the head 6. Head 6 is semi-spherically socketed at the top to receive a ball member 8 which, together with the head 6, forms a universal ball and socket joint between the fork and a shield support 9. The upper ends of fork members 7 are bent around ball 8 so as to positively hold it in contact with its seat and to frictionally retain it in any set position. The support 9 has spring jaws 10 which are adapted to

frictionally retain a shield 11 by snapping into grooves 12 in the shield. My device is clamped or frictionally held to the tool post of a lathe, to the bed of a shaper or in front of the wheel of a grinder so as to be between the workman's eyes and the work. By use of my modified form, the shield may be readily adjusted to any desired position, the shield is quickly removable from the support and the entire device is frictionally held in place. The advantages in the use of a shield are in the protection given the workman's eyes and face.

While I have shown a particular form of embodiment of my invention, I am aware that many minor changes therein will readily suggest themselves to others skilled in the art without departing from the spirit and scope of the invention, and I therefore desire to avoid being limited to the exact form shown and described except as pointed out in the appended claims.

Having described my invention, what I claim as new and desire to protect by Letters Patent, is—

1. In a device of the class described, the combination of a longitudinally grooved transparent eye shield, a spring jawed shield supporting member which frictionally holds said shield by the coöperation of said jaws with the groove in the shield, whereby the said shield may be easily removed.

2. In a device of the class described, the combination of a longitudinally grooved transparent eye shield, a spring jawed shield supporting member which frictionally holds said shield by the coöperation of said jaws with the groove in the shield, whereby the shield may be easily removed, and spring clamp members adjustably attached to said shield supporting member.

3. In a device of the class described, the combination of a transparent eye shield, a shield supporting member which frictionally grips the said shield, a frictionally held clamp member which is adapted to be removably attachable to the tool post of a lathe or the like, and a joint between the said shield support and the said clamp member, whereby adjustment between the said members may be made.

WILLIAM E. SCHMIDT.
